James J. Davis of New York, N.Y.

Designer to

Mitchell Yance & Co. of New York.

Letter Patent No. 3330. Dated May 29, 1866.

Design for a Chandelier.

The schedule referred to in these Letters Patent and making part of the same.

To all whom it may concern:

Be it known that I, James Frederick Davis, of the County and State of New York, have invented a new Design for a Chandelier, as follows; and I do hereby declare that the following is a full, clear and exact description of the same, reference being had to the accompanying photographs forming part of this specification.

The general character of my design is Roman. The upper part consists of a short shaft, a, having an ornamental capital, b, and terminating at its bottom in an ornamental base, c, with the sides of which there are connected the upper parts of curved pendants, d, the lower parts of which connect with the base of a pedestal, e, on which there is arranged centrally between the pendants, d, a statue of Bellona.

From the lower part of each pendant, d, there springs a curved bracket, f; and between the pendants, d, there are larger brackets, g, f, springing from the base of the pedestal, e, the portions, g, of the latter brackets resembling the lower portions of the pendants, d, and the portions, f, resembling the brackets, f, attached to the said pendants.

The configuration and ornamentation of the several members of the design are clearly represented in the photograph, and can be better understood by reference thereto, than by any detail description.

It is I claim, and desire to secure by Letters Patent in, The design and configuration of the character or gasolier herein described and represented in the accompanying photograph.
